DESIGN FOR A PEN HOLDER DESK STAND

Ray R. Hutcheson, Queens, N. Y., assignor to J. Harris and Company, New York, N. Y.

Application July 31, 1935, Serial No. 57,886

Term of patent 3½ years

To all whom it may concern:

Be it known that I Ray R. Hutcheson, a citizen of the United States, residing in Queens, county of Queens, and State of New York, have invented a new, original, and ornamental Design for a Pen Holder Desk Stand, of which the following is a specification, reference being had to the accompanying drawing, forming a part thereof, in which:

Fig. 1 is a side elevational view of the pen holder desk stand according to my invention.

Fig. 2 is a front elevational view of Fig. 1 and Fig. 3 is a plan view of Fig. 1.

I claim:—

The ornamental design for a pen holder desk stand, substantially as shown.

Signed at New York, in the county of New York and State of New York, this 26 day of July, 1935, A. D.

RAY R. HUTCHESON.
